LINT REMOVER

David A. Martin, 2375 Colgate Drive,
Costa Mesa, Calif. 92626

Filed Feb. 23, 1966, Ser. No. 1,152

Term of patent 14 years

(Cl. D9—2)

FIG.-1

FIG.-2

FIG.-3

FIG.-4

FIG.-5

FIG.-6

FIG. 1 is a bottom perspective view of a lint remover, showing my new design;

FIG. 2 is a bottom plan view thereof;

FIG. 3 is an end elevational view thereof;

FIG. 4 is a side elevational view thereof;

FIG. 5 is a top plan view thereof; and

FIG. 6 is a top plan showing the handle in non-operating position.

I claim:

The ornamental design for a lint remover, as shown and described.
